CLAIM

I claim the ornamental design for an induction heating cooker, as shown and described.

DESCRIPTION

FIG. 1 is a top front perspective view of an induction heating cooker of the present invention;

FIG. 2 is a top rear perspective view thereof;

FIG. 3 is a top view thereof;

FIG. 4 is a front view thereof;

FIG. 5 is a bottom view thereof;

FIG. 6 is a rear view thereof;

FIG. 7 is a first side view thereof; and,

FIG. 8 is a second side view thereof.

The ornamental design which is claimed is shown in solid lines in the drawings. Any broken lines in the drawings are for illustrative purposes only and form no part of the claimed design.
